UNITED STATES PATENT OFFICE.

JOHN MURCEK, OF HAZLETON, PENNSYLVANIA.

LAMP-EXTINGUISHER.

Specification of Letters Patent. Patented Sept. 18, 1917.

1,240,475.

Application filed April 10, 1917. Serial No. 160,953.

To all whom it may concern:

Be it known that I, JOHN MURCEK, a citizen of the United States, residing at Hazleton, in the county of Luzerne and State of Pennsylvania, have invented certain new and useful Improvements in Lamp-Extinguishers, of which the following is a specification.

This invention relates to certain new and useful improvements in lamp extinguishers.

The primary object of the invention is the provision of an extinguisher or snuffer for lamps such as kerosene or coal oil lamps, the same being automatically operable for extinguishing the light upon turning down the wick of the lamp.

A further object of the invention is the provision of an extinguisher in the form of an attachment for burners of that variety employing an oil contacting wick, the light being readily extinguished upon turning down the wick and rendered ready for lighting upon again elevating the wick, provision being made for the free movement of the wick through the burner without interruption by the extinguishing device.

While it is understood that lamp extinguishers have been heretofore provided for operative shifting transversely of the path of movement of a burner wick, such is not now broadly claimed but the gist of my invention resides in an extinguisher of this general type adapted for ready arrangement in its inoperative position permitting free movement of the wick unaffected by the extinguisher during such times, for instance, as the initial insertion of the wick within the burner.

With these general objects in view and others that will appear as the nature of the invention is better understood, the same consists in the novel construction, combination and arrangement of parts hereinafter fully described, illustrated in the accompanying drawing and pointed out in the appended claim.

In the drawing forming a part of this application and in which like numerals refer to corresponding parts throughout the several views.

Figure 1 is a vertical diametrical sectional view of an ordinary form of lamp burner provided with the present device, the latter being indicated by dotted lines in the extinguishing position.

Fig. 2 is a side elevation thereof with parts broken away, the extinguisher being indicated by dotted lines in its inactive released arrangement.

Fig. 3 is a top plan view of the structure shown in Fig. 1 with the guard cap removed.

Fig. 4 is a detail vertical central sectional view through the burner with the extinguisher in its released arrangement.

Fig. 5 is a perspective view of the usual wick tube altered for the convenient mounting of the extinguisher thereon.

Fig. 6 is a perspective view of the extinguisher detached, and,

Fig. 7 is a plan view of the metal blank from which the extinguisher is preferably formed.

The present embodiment of my invention is herein illustrated in connection with the well known form of burner 10 employed with wick lamps and comprising a chimney mounting circular base 11 having chimney retaining springs 12 and provided with a centrally arranged wick tube 13 for accommodating a wick 14 slidably therein and longitudinally operable by means of a turn shaft 15 having a plurality of toothed wheels 16 which engage the said wick through side slots 17 in the said tube. The tube 13 has an overlapped crimped longitudinal jointure or seam 18 while a protecting cap 19 is hinged as at 20 to the base 11.

A manner of attaching an extinguisher to a burner of the above described well known structure consists in forming the extinguisher or snuffer 21 preferably from a single piece of sheet metal and hinging the same to a modified portion of the seam 18 of the wick tube 13 as at 22. The attaching means herein illustrated consists in forming parallel lugs 23 from the side portions of the seam 18 at an interrupted point 24 therein, the said lugs having suitable journaling perforations 25 and it being understood that the interruption of the seam 18 provides an open slot permitting free access to the interior of the tube 13 and to the wick 14 positioned therein.

The snuffer 21 is formed of a substantially T-shaped metal blank 26 having the cross-member 27 bent into angle-iron arrangement providing a flange 28 perpendicularly projecting from the top of the blank 26. The upright portion 29 of the blank 26 has the opposite halves bent in-

wardly into engagement with each other forming an attaching leg 30 provided with a foot 31 arranged with a perforation 32 therethrough adapted for the reception of a pivoting pin 33 for hinging the said foot 31 between the lugs 23 with the pin 33 arranged through the perforations 25 of the latter.

The foot 31 has a serrated toe portion 34 in the form of teeth which project through the interrupted seam portion 24 into engagement with the wick 14 when the snuffer is vertically or obliquely arranged as best illustrated in Fig. 1 of the drawing while the 10 pivoted end of the snuffer has a curved face 35 forming the bottom of the foot 31 which lies within the interruption or slot 24 of the tube when the snuffer 21 is substantially horizontally positioned, thereby permitting free longitudinal movement of the wick 14 as best illustrated in Fig. 4.

From this detail description of the invention it will be understood that the extinguisher 21 may be pivotally mounted 15 upon the tube 13 in any manner permitting a portion thereof such as the foot 31 to be free from interference with the wick 14 when in one position but arranging another portion of the extinguisher such as the teeth 20 34 so as to normally engage the wick 14 whereby the extinguisher is automatically projected over the upper open end of the tube 13 and withdrawn therefrom upon the shifting of the wick 14 downwardly and 25 upwardly respectively through the operation of the usual wick operating turn shaft 15. When it is desired to insert or withdraw the wick 14 from the tube 13 the cap 19 is opened and the extinguisher 21 moved downwardly to a substantially horizontal position 30 upon the base 11 as illustrated in Fig. 4 of the drawing as well as by dotted lines in Fig. 2 thereof, it being noted that in the latter view the cap 19 has been closed 35 which may retain the extinguisher 21 inactive by reason of the inwardly flaring portion 36 of the cap 19.

When the wick 14 is properly arranged 40 within the tube 13, the extinguisher 21 is swung to its vertical position with the flange 28 overlying the upper end of the tube 13 and the wick 14 and at which times the teeth 34 will be in their operative engagement with the wick 14. Upon turning the shaft 45 15 for elevating the wick 14, the extinguisher 21 is pivotally moved outwardly withdraw-

ing the flange 28 from the tube and wick and exposing the latter for purposes of lighting as illustrated in Figs. 1 and 3 while a reverse turning of the shaft 15 in the direction indicated by the arrows in Fig. 1, lowers the wick 14 and returns the snuffer 21 to its vertical position with the flange 28 thereof overlying the tube and the wick and thereby extinguishing the latter as illustrated in Fig. 60 2 of the drawing as well as by dotted lines in Fig. 1 thereof. When the snuffer 21 is normally arranged for operative movement in the manner described after the wick has been initially inserted in the burner, the 65 snuffer 21 is prevented from assuming its inactive horizontal position by reason of the fact that any continued upward movement of the wick 14 tending to depress the snuffer would bring the latter into contact 70 with the central portion 36 of the cap 19, this engagement insures the operative positioning of the snuffer at all times when the cap 19 is closed after the snuffer has been once positioned operatively to permit the 75 release of the snuffer 21 from the wick whenever required by opening the cap 19 and pivotally moving the snuffer 21 to its horizontal position.

The base 11 may be provided with a slot 80 37 adjacent the tube 13 and beneath the lugs 23 if desired for accommodation of the swinging movement of the snuffer 21 while the opposite ends of the flange 28 of the snuffer may be inclined as at 38.

A serviceable extinguisher for lamps is arranged in the nature of a burner attachment, the same being easy and inexpensive to manufacture as well as to install the main feature thereof consisting in its adaptability 95 for inoperative positioning when desired to insert or withdraw a wick such as during the renewing thereof.

What I claim as new is:—

An extinguisher attachment for burners 100 comprising a single piece snuffer formed from a T-shaped blank and having an angularly bent flange at one end, the upright portion of the blank being centrally bent inwardly with the sides thereof in engagement with each other forming a leg, and each of said sides having a terminal foot with teeth at their free ends adapted for coöperation when assembled.

In testimony whereof I affix my signature. 110

JOHN MURCEK.
